SKATE

Boleslawa H. Celmer, Detroit, Mich.

Application September 19, 1944, Serial No. 554,777

4 Claims. (Cl. 280—11.19)

This invention relates to skates and has relation more particularly to an article of this kind especially designed and adapted for use by a toe dancer, and it is primarily an object of the invention to provide a skate having means which, when applied to a foot of the dancer, will enable the instep of the foot to arch within the area of the skate and thereby give the foot equal balance as the surface engaging element of the skate will be at the center of the arched instep.

It is also an object of the invention to provide a skate of this kind wherein the heel portion of the skate is supported by the toe portion in a manner to further assure the desired equilibrium.

The invention consists in the details of construction and in the combination and arrangement of the several parts of my improved skates whereby certain important advantages are attained, as will be hereinafter more fully set forth.

In order that my invention may be the better understood, I will now proceed to describe the same with reference to the accompanying drawing, wherein:

Figure 1 is a view in side elevation of the skate showing the same in use;

Figure 2 is a rear elevation of the same; and

Figure 3 is a section on the line 3—3 of Figure 1.

In the embodiment of the invention as illustrated in the accompanying drawing, the surface engaging element is here shown as being in the form of a roller, although it is believed to be readily understood that the skate may have such surface engaging element in the form of a blade for use on ice. The substitution of one form of surface engaging member for another is believed to be obvious and, therefore, a detailed description and illustration of the two forms is believed to be unnecessary.

In the embodiment of the invention as illustrated in the accompanying drawing, C denotes a toe cup of desired size and design and which is adapted to receive the toe portion of a slipper S herein disclosed as of a style generally used by toe dancers. The cup C at its rear is provided with the sole plate 4 which is suitably secured, as at 2, to the sole 3 of the slipper S.

The outer extremity of the toe cup C is provided with a rearwardly directed rigid plate 4 of desired configuration and form and the outer extremity of this plate 4 carries an upstanding socket 5 in which is threaded the lower end portion of a rod 6 of desired length.

This rod 6 extends inwardly of the slipper

S at substantially right angles to the plate 4 and has its outer or upper portion telescopically received within an elongated sleeve 7 hingedly connected, as at 8, to a plate 9 which is securely fixed, as at 10, to the heel portion of the slipper sole 3.

Interposed between the socket 5 and the sleeve 7 is an expandable member 11, herein disclosed as a coil spring, encircling the rod 6. The member 11 or spring 11 has a tendency to exert such pressure which would tend to straighten or flatten out the sole 3 and it is, therefore, important and necessary to limit the extent of action of the rod 6 with a resultant regulation or control of the flexing of the sole 3.

In the present embodiment of the invention, the arch or central portion of the sole 3 has secured thereto, as at 12, the outer end portions of the longitudinally disposed plates 14 directed one toward the other with the inner portions of said plates 14 overlapping. The outermost plate 14 is provided therealong in its central portion with the slot 15 through which is directed a lug or part 16. It is believed to be obvious that the extent of flexing movement of the sole 3 or the extent of relative movement of the sleeve 7 along the rod 6 will be limited by contact of the lug or part 16 with the opposite end edges of the slot 15.

The outer end portions 17 of the plates 14, which are secured to the sole 3, are in predetermined angular relation with respect to the plates 14 proper and as may be determined to best meet with the requirements of practice. It is believed to be obvious that the plates 14 coact in a manner to hold the back or heel portion of the sole 3 arched back and against flattening out when the foot is off the floor which is very necessary in order to maintain the sole of the slipper in proper form. It is also believed to be obvious that the spring 11 will allow for more arching of the instep within the limitations afforded by the slot 15.

The outer extremity of the cup C carries suitably mounted rollers R although it is believed to be obvious that if desired a runner, such as used for ice skates, could be used without in any way departing from the scope of the present invention and without requiring any detailed description or illustration showing the embodiment of the invention employing the ice skate runner.

In practice, when the rollers R start the glide, the toe leads and the pressure is centered on the toe. When placed well on the floor, the pressure goes onto the heel and works on the rod, resulting in the instep arching out and the toes of the

dancer are then only used for directing the glide. The rollers effectively glide since they are free from either the pressure of the rod and the toe as it is to be noted that the rollers R are exactly in the center between the toe cup C and the rod 6.

From the foregoing description it is thought to be obvious that a skate constructed in accordance with my invention is particularly well adapted for use by reason of the convenience and facility with which it may be assembled and operated.

What is claimed is:

1. Foot gear for a toe dancer comprising a slipper having a flexible sole, a rigid cup in which the toe portion of the slipper is placed, means for fixing the toe portion of the sole to the cup, a rigid member carried by the outer extremity of the toe cup and extending substantially perpendicular to the sole toe portion, a yieldable connection between the outer end of the rigid member and the heel portion of the sole of the slipper, and a surface engaging element carried by the toe cup.

2. Foot gear for a toe dancer comprising a slipper having a flexible sole, a rigid cup in which the toe portion of the slipper is placed, the cup terminating short of the sole instep portion whereby the arching of such portion is permitted, means for fixing the toe portion of the sole to the cup, a rigid plate carried by the outer extremity

5 of the toe cup and extending substantially perpendicular to the sole toe portion, a yieldable connection between the outer end of the plate and the heel portion of the sole of the slipper, a surface engaging element carried by the toe cup, and means for limiting the extent of arching of the sole at the said instep portion thereof.

3. Foot gear for a toe dancer as set forth in claim 2 wherein the means for limiting the extent 10 of arching of the sole at the insole portion thereof comprises two overlapping plates extending lengthwise of the sole, means for securing the outer extremities of the plates to the sole, one of said plates having a slot extending therealong, and a part carried by the second plate extending within the slot of the first plate.

4. Foot gear for a toe dancer as set forth in claim 1, wherein the yieldable connection between the rigid member of the toe cup and the heel portion of the sole of the slipper comprises a rod, 20 means for connecting said rod at one end to the rigid member, a sleeve pivotally connected with the heel portion of the sole and having the other end of the rod telescopically extended thereinto, 25 and an expansible member exerting pressure on the sleeve for constantly urging movement of the sleeve on the rod away from the member.
